CONTACT STRUCTURE FOR ELECTRIC SWITCHES

Richard P. Ballou and Daniel F. Daly, Hartford, Conn., assignors to Federal Electric Products Company, Newark, N. J., a corporation

Application July 14, 1948, Serial No. 38,686

15 Claims. (Cl. 200—166)

1

This invention relates generally to the contactor type of electric switches and more particularly to the movable bridge contact structures therefor.

Each pole of a contactor type of electric switch comprises two separated stationary terminal contacts, mounted upon a fixed block of insulating material and serially spaced thereon sufficiently apart so as to prevent the establishment of the circuit by arcing. Completion of the circuit is obtained through the application of a movable bridge contact member to each pair of serially stationary contacts. Each bridge contact member is mounted within a holder providing a resilient mounting thereby rendering the bridge contact member capable of self alignment and adjustment so that proper contact surface with its related pair of serially stationary contacts is secured. The bridge contact structure is secured to a movable carriage of insulating material carried by a suitable operating mechanism adapted for displacement in a vertical direction. Upon actuation, the operating mechanism develops the necessary force to bring the movable bridge contact member into engagement with its respective pair of stationary contacts.

In a prior contactor type of electric switch, the attachment of the bridge contact structure was obtained by means of a movable pin, the vertical displacement of which permitted only the removal of the bridge contact member. In order to provide the proper maintenance for the contactor type of electric switch, it is not only necessary at times to inspect and clean the bridge contact members but also to replace the resilient-mounting of the contact holder. Removal of the entire bridge contact structure is obtained by the withdrawal of the pin which necessitated the removal of the insulated carriage from the armature of the electromagnet.

In another contactor type of switch, such as that shown in Patent No. 2,359,605, the contact structure can be removed as a unit from the carriage, while the latter remains in place, but the construction was such as to require the provision of a metal stud fixed in the insulation block of the carriage for engaging one of the members of the contact structure for holding the latter in position. The present invention retains the advantages of the construction shown by said patent but obviates the need for said stud and also obviates the pin by which the contact member is removably held in position on the holder of the contact structure.

2

An important feature of the present invention is that the bridge contact structure does not require a pin or stud for its attachment to the insulated carriage but automatically and positively locks onto and maintains itself thereupon in response to the exercise of slight manual pressure upon its holder during its insertion into position. Removal of the bridge contact structure is also easily effected by the exertion on the holder of slight pressure which unlocks the structure thereby permitting its withdrawal without the necessity of dismantling the insulated carriage from the armature of the electro-magnet. The provision of these features constitutes one object of the invention.

Another object is the provision of a contact structure or unit in which the several members thereof are releasably held together by a spring which also maintains contact pressure and releasably holds the lock element of the unit in locking engagement with the carriage when the unit is mounted therein.

A further object of the invention is generally to improve the construction and operation of contactor type electric switches and bridge contact structures therefor.

The foregoing and other objects and advantages of the invention will appear more fully hereinafter from a consideration of the detailed description which follows, taken together with the accompanying drawings. It is to be expressly understood, however, that the drawings are for illustrative purposes only and are not to be construed as defining the limits of the invention.

In the drawings, wherein like reference numerals refer to like parts:

Fig. 1 is a front elevation of a contactor type electric switch embodying the present invention showing the relationship of the stationary contacts with respect to their respective bridge contact structures;

Fig. 2 is a section elevation taken along line 2—2 of Fig. 1 showing the relationship of a pair of stationary contacts with respect to its bridge contact structure and the manner in which said bridge contact structure locks onto and maintains itself upon the movable carriage;

Fig. 3 is a perspective view of the component parts constituting the bridge contact structure of this invention;

Fig. 4 is a fragmentary perspective view, partly in section along line 2—2 of Fig. 1, showing the movable carriage in which the bridge

contact structure is automatically releasably locked;

Fig. 5 is a view on the line 5—5 of Fig. 2;

Fig. 6 is a view similar to Fig. 2 showing another form of the invention, the stationary contact structure being omitted;

Figs. 7 and 8 are side and bottom views, respectively, of the latch member shown in Fig. 6;

Fig. 9 is a view similar to Fig. 4, showing the insulation carriage in the form of the invention illustrated by Fig. 6; and

Fig. 10 is a perspective view of the contact holder in the form of the invention illustrated in Fig. 6.

As here shown (Fig. 1), the switch to which the present invention relates comprises a plurality of poles, each pole being of identical structure. Since the poles are of identical structure, the operation of a single pole 1 is sufficient to demonstrate the invention of this application. Each of said poles comprises two stationary contacts 2 and 3 to which are respectively connected the incoming and outgoing wires of its branch of the circuit. Stationary contacts 2 and 3 are mounted upon a fixed block of insulating material 4 and serially spaced thereon sufficiently apart so as to prevent the establishment of a circuit by arcing. Fixed block of insulating material 4 is rigidly attached to a frame 5 for support thereby.

Bridge contact structure 6 through its bridge contact member 7 provides the means of bridging the gap between fixed contacts 2 and 3 to close the electrical circuit. Bridge contact structure 6 shown in Fig. 2 is mounted upon an insulated carriage 8 supported for displacement in a vertical direction by a suitable operating mechanism 9. Operating mechanism 9 may be either electrically or mechanically actuated. The actuation of operating mechanism 9 brings bridge contact structure 6 into contact with fixed contacts 2 and 3 thereby bridging the gap to obtain the closure of the electrical circuit. Upon the release of operating mechanism 9, bridge contact structure 6 drops away from fixed contacts 2 and 3 for opening the electrical circuit.

Bridge contact structure 6 comprises bridge contact member 7, helical spring 10, latch 11, and holder 12 as shown in Figs. 2 and 3. Bridge contact member 7 comprises an elongated, preferably rigid, metal bar 13 to whose top surface are rigidly secured oval faced contacts 14 and 15 at the respective ends thereof. Midway between contacts 14 and 15, the respective side edges of bar 13 are provided with identical rectangular notches 17 and 18 while the underside of said bar is provided with a circular boss 16 pressed therefrom. The supporting means for bridge contact member 7 comprises a holder 12 which has a horizontal bottom or abutment member 19, the integrally connected spaced upstanding arms 20 and 21 adjacent one end thereof and lateral projections or fingers 22 and 23 near its other end. Arms 20 and 21, respectively, set loosely into notches 17 and 18 of bridge contact member 7 restrain movement of the latter in the direction of its length. The upper ends of arms 20 and 21 are reflexed inwardly and constitute abutments 24 and 25, respectively, which overlie the upper face of contact member 7 at its intermediate portion and limit the outward position thereof. Approximately midway between arms 20, 21 and fingers 22, 23 along its longitudinal centerline, bottom member 19 of holder 12 is provided with a rectangular slot 26.

Latch 11 comprises horizontal body member 27 and the integrally connected downwardly projecting tongue 28 whose purpose will become subsequently apparent. Latch 11 sets loosely upon the upper surface of bottom member 19 of holder 12 in such manner that tongue 28 projects through slot 26 of said holder. In order to maintain latch 11 in position in holder 12 and yet permit the free movement of latch 11 about the back edge of bottom member 19 of holder 12 as a pivot, the side edges of horizontal member 27 are provided with rectangular notches 29 and 30 into which arms 20 and 21 of holder 12, respectively, loosely fit. Midway between rectangular notches 29 and 30, the upper surface of member 27 is provided with a punched boss 31. Bridge contact member 7 is supported on helical spring 10 one end of which fits around boss 16 of bar 13 and the other of which fits around boss 31 of latch 11. Bosses 16 and 31, thus hold spring 10 to prevent its movement out of position. Spring 10 yieldingly maintains bridge contact member 7 against the respective undersides of abutments 24 and 25 of holder 12 thereby holding said bridge contact member in an elevated and operative position when the switch is open. Spring 10 constitutes a universal or rocking seat on which bridge contact member 7 can rock to align itself in contact with stationary contacts 2 and 3. When the switch is closed, bridge contact member 7 may be depressed below abutments 24 and 25 sufficiently to resiliently engage the companion stationary contacts 2 and 3 by the pressure of spring 10.

Bridge contact member 7 may be withdrawn from holder 12 by the vertical depression of said bridge contact member below abutments 24 and 25 sufficiently to permit its being turned edgewise, about its longitudinal axis to permit the said bridge contact member to be withdrawn through the space between abutments 24 and 25. Spring 10 may remain in place, being held between latch 11 and abutments 24 and 25. In a reverse process of operation, bridge contact member 7 is inserted into holder 12 by turning said bridge contact member edgewise and depressing therewith spring 10 sufficiently below the undersides of abutments 24 and 25 to permit the turning thereof into a horizontal position upon which attainment the said bridge contact member is maintained in position by spring 10.

Insulated carriage 8 is provided with a rectangular recess 32 extending to the front face thereof, as shown in Figs. 2, 4 and 5, wherein the lower portion of bridge contact structure 6 is received, the flat bottom 33 of said recess being wide enough to freely accommodate bottom member 19 of holder 12 but not wide enough to receive fingers 22 and 23. In order to permit holder 12 to be inserted in recess 32, the bottom portion of the front face of insulated carriage 8 is cut away providing rectangular recess 34 whose width freely accommodates fingers 22 and 23 and whose top surface 35 extends above the flat bottom 33 of recess 32 by an amount just sufficient to permit passage of the top surfaces of fingers 22 and 23. The front portion of the flat bottom 33 of recess 32 is slightly inclined and recessed to facilitate the insertion of bridge contact structure 6 into position. Flat bottom 33 of rectangular recess 32 is provided with angular groove 36 whose purpose will become subsequently apparent.

The bridge contact structure comprising the above described assembly of contact member 7,

latch 11 and spring 10 in holder 12 may be readily placed in position in the companion recess 32 of carriage 8 and readily removed from the latter as a unit.

In order to insert the unitary bridge contact structure in position in the carriage 8, said structure is moved through the forward end of the companion recess 32 until the projections 22 and 23 engage the front surface portions 33' of carriage 8 at opposite sides of the recess above the surfaces 35 of front recess 34. Then the outer end of holder 12 is moved downwardly so as to bring projections 22 and 23 into registry with recess 34 below said surfaces 35, whereupon continued inward movement of the contact structure may be effected for disposing the latter in its operative position, with tongue 28 of latch 11 in catch-recess 36, with the inner end portion 40 of said latch member projecting through inner end-opening 38 of recess 32, and with fingers 22 and 23 of holder 12 adjacent surface 37 of the front recess 34 of carriage member 8. It will be noted that the bent end portion 44 at the outer end of holder 12 provides a finger piece for facilitating the insertion and removal of the bridge contact structure. A guide groove 45, slightly wider than tongue 28, receives the latter during the inward movement of the contact structure unit in recess 32.

When it is desired to remove a bridge contact structure from the carriage 8, pressure is exerted on finger piece 44 of holder 12 for moving the latter a short distance inwardly in recess 32, to provide for clearance of tongue 28 from the forward end 33a of recess 36. While the structure is in this inwardly displaced position, holder 12 is pivoted downwardly on the outer edge 46 of the bottom 33 of recess 32, with the result that the inner end 48 of holder 12 presses upwardly against latch 11 against spring 10. During this movement of holder 12, the inner end portion 40 of latch 11 engages shoulder 42 adjacent its end 50 as a fulcrum about which said latch pivots, in a clockwise direction viewing Fig. 2, whereby the tongue of said latch is released from catch-recess 36. This allows the contact structure to be moved forwardly of recess 32 completely out of the latter.

The above described construction constitutes the presently preferred embodiment of the invention, but in Figs. 6 to 10 another form of the invention is illustrated and will now be described. In this form of the invention, the contact holder 12a is of substantially the same construction as contact holder 12 but is longer than the latter so that its rear part 48a extends under the shoulder 42a of the insulation carriage 8a. The latch member 11a corresponds to latch member 11, but as here shown, latch member 11a has a stud 52 which is received in a catch-recess 54 provided in the bottom 33a of the recess or groove 32a in which the contact structure is releasably mounted. As here shown, the peripheral wall of recess 54 is perpendicular to the bottom of recess 32a, so that when catch stud 52 is disposed in recess 54 the contact structure is locked against movement in recess 32a of the carriage, and so that latch member 11a can be released only by positive movement thereof for withdrawing catch stud 52 from said catch-recess. It will be noted that the slot 26a in holder 12a extends forwardly and that the latch member 11a is provided with a part 56 which extends through said slot and terminates in a forward free end portion 58 near the forward free

end portion or finger piece 44a of the contact holder 12a. When it is desired to remove the contact structure from the recess 32a of the carriage, end portions 44a and 58 of holder 12a and latch member 11a respectively are gripped for pressing end portion 58 of latch member 11a toward holder 12a. Since shoulder 42a overhangs the end portion 40a of contact holder 12a, the pressure just referred to results in upward movement of the latch member 11a thereby withdrawing the catch stud 52 from the catch recess 54, so that the contact structure can be removed from recess 32a through the front open end of the latter. In other respects, the contact structure shown in Figs. 6 to 10 is the same as the contact structure shown in Figs. 1 to 5 and the corresponding elements and parts thereof are designated by the same reference numerals respectively with the letter "a" added. It will be noted, however, that the rear end portion 40a of the latch member is flat and terminates short of the rear edge portion 48a of the contact holder 12a, so that the rear end of the latch member pivots on the upper surface of contact holder 12a when said latch member is operated, as hereinbefore described, for releasing the contact structure from the carriage 8a to permit the removal of said contact structure from said carriage. It will be understood that arms 20a and 21a of the contact holder 12a slidably engage the opposite side walls of the companion recess 32a and that fingers 22a and 23a of the contact holder are received under the surfaces 35a of the carriage in front recess 34a in the same manner as the fingers 22 and 23 of holder 12, in front recess 34, and it will be noted that when the fingers 22a and 23a are disposed below the surfaces 35a of said forward recess 34a, contact holder 12a is held positively at both ends against upward movement.

It will be apparent to those skilled in the art that a novel bridge contact structure for a contactor type of electric switch has been provided by the present invention which automatically locks and maintains itself upon a movable carriage without the necessity of other attaching elements. Such bridge contact structure providing at the same time for its contact member a resilient mounting rendering it capable of self alignment and adjustment thereby obtaining the proper contact surface with its related pair of stationary contacts.

Although but one embodiment of the invention has been illustrated and described in detail, various changes and modifications in the form and relative arrangement of parts which will now appear to those skilled in the art, may be made without departing from the scope of the invention.

Having thus described our invention, what we claim and desire to secure by Letters Patent is:

1. A contact structure for an electric switch, comprising a contact bar provided with notches in its opposite side edges, a holder in which said contact bar is positioned for movement therein in opposite directions transversely of its length, said holder having parts which engage said bar in said notches for preventing movement of said bar in the direction of its length, said holder having reflexed confronting portions releasably engageable with said bar for limiting the movement thereof in one of said opposite directions, and spring means carried by said holder and yieldably holding said bar against movement in the other of said opposite directions, said portions

being spaced from each other for the edgewise passage of said bar therebetween to effect the ready removal of said bar from said holder and the ready insertion of said bar therein, said spring means being retained in said holder by said portions when said bar is out of said holder.

2. A contact structure for an electric switch, comprising a contact bar provided with notches in its opposite side edges, a holder in which said contact bar is positioned for movement therein in opposite directions transversely of its length, said holder having laterally spaced arms which engage said bar in said notches for preventing movement of said bar in the direction of its length, said arms having inturned end portions which overlie said bar for limiting the movement thereof in one of said opposite directions, and spring means positioned between said arms and yieldably holding said bar against movement in the other of said opposite directions, said portions being spaced from each other for the edgewise passage of said bar therebetween to effect the ready removal of said bar from said holder and the ready insertion of said bar therein, said spring means being retained in said holder by said portions when said bar is out of said holder.

3. A contact structure for an electric switch, comprising a contact bar provided with notches in its opposite side edges, a holder in which said contact bar is positioned for movement therein in opposite directions transversely of its length, said holder having parts which engage said bar in said notches for preventing movement of said bar in the direction of its length, said holder having portions releasably engageable with said bar for limiting the movement thereof in one of said opposite directions, a latching member movably mounted in said holder and releasably engaging said switch for releasably holding said contact structure therein, and spring means bearing at its opposite ends against said bar and said latching member, respectively, for yieldably opposing movement of said bar in the other of said directions and for yieldably holding said latching member in position in said holder.

4. In an electric switch, an insulating supporting carriage, a contact holder having an abutment member in normal engagement with said carriage and spaced upstanding arms provided with inturned projections at the upper ends of said arms, a contact member located between said arms and in normal engagement with said projections, a latch member located between said arms, said latch member being in normal engagement with said abutment and in latching engagement with said supporting carriage, and spring means yieldably holding said contact member in the aforesaid relation, said spring means also in collaboration with said latch constituting the means of locking said abutment member onto said supporting carriage.

5. In an electric switch, an insulating supporting carriage, a contact holder having an abutment member in normal engagement with said carriage and spaced upstanding arms provided with inturned projections at the upper ends of said arms, a contact member located between said arms and in normal engagement with said projections, a latch member located between said arms, said latch member being in normal engagement with said abutment and in latching engagement with said supporting carriage, and a spring bearing and releasably held upon said latch and against said contact member, said spring holding

said contact member yieldably in position against said projections and also in collaboration with said latch constituting the means of locking said abutment member onto said supporting carriage.

6. In an electric switch, an insulating supporting carriage having a rectangular recess therein, a contact supporting frame having a bottom member seated upon the bottom of said recess, spaced upstanding arms engaging the sides of said recess and extending above said carriage the said upper arms being provided with inturned opposed ends constituting abutments, and spaced horizontally projecting fingers extending beyond the sides of said recess, a second rectangular recess in said supporting carriage extending sidewise beyond the said projecting fingers and providing bearing surfaces for the top faces of said projecting fingers, a contact member located between said arms and having its upper face bearing against said abutments, a latch member located within said arms, the front end thereof being in latching engagement with the bottom of the first recess and the back end thereof bearing upon the rear edge of the bottom member of said contact supporting frame, and spring means located within the space between the contact member and the latch and bearing against the underside of said contact member and also against the top side of said latch, said spring means yielding holding said contact member in the aforesaid relation and also in collaboration with said latch locking the contact supporting frame onto the said insulating carriage.

7. In an electric switch, an insulating supporting carriage having a rectangular recess therein, the bottom of said recess being provided with an angular groove, a contact supporting frame having a bottom member seated upon the bottom of said recess, said bottom member being provided with an elongated slot, integrally connected spaced upstanding arms engaging the sides of said recess and extending above said carriage, the said upstanding arms being provided with inturned opposed ends constituting abutments; and integrally connected spaced horizontally projecting fingers extending beyond the sides of said recess, a second rectangular recess in said supporting carriage extending sidewise beyond the said projecting fingers and providing bearing surfaces for the top faces of said projecting fingers, a contact member located within said arms and having its upper face bearing against said abutments, a latch member located within said arms, comprising a downwardly projecting tongue and also a body, said tongue projecting downwardly through the elongated slot of the bottom member of said contact supporting frame into the angular groove of the bottom of the first rectangular recess and the said body bearing upon the upper rear edge of the bottom member of said contact supporting frame, and spring means located within the space between the contact member and the latch and bearing against the underside of said contact member and also against the top side of said latch, said spring means yieldably holding said contact member in the aforesaid relation and also in collaboration with said latch locking the contact supporting frame onto the said insulating carriage.

8. In an electric switch, an insulating supporting carriage having a rectangular recess therein, the bottom of said recess being provided with an angular groove, a contact supporting frame having a bottom member seated upon the bottom of said recess, said bottom member being provided

with an elongated slot, integrally connected spaced upstanding arms engaging the sides of said recess and extending above said carriage, the said upstanding arms being provided with inturned opposed ends constituting abutments, and integrally connected spaced horizontally projecting fingers extending beyond the sides of said recess, a second rectangular recess in said supporting carriage extending sidewise beyond the said projecting fingers and providing bearing surfaces for the top faces of said projecting fingers, a contact member located within said arms and having its upper face bearing against said abutments, a latch member, located within said arms, comprising a downwardly projecting tongue and a body, said tongue projecting downwardly through the elongated slot of the bottom member of said contact supporting frame into the angular groove of the bottom of the first rectangular recess and said body bearing upon the upper rear edge of the bottom member of said contact supporting frame, and spring means located within the space between the contact member and the latch and bearing against the underside of said contact member and also against the top side of said latch, said spring means yieldably holding said contact member in the aforesaid relation and also urging said latch downwardly against the bottom member of said contact supporting frame and also into the angular groove of said first rectangular recess to prevent the horizontal displacement of said contact supporting frame thereby locking the said contact supporting frame onto the said insulating supporting carriage.

9. In an electric switch, a contact holder having opposed abutments, a contact member movably mounted within said holder, said contact member comprising end contact faces and an intermediate supporting portion having a bossed surface portion projecting from one side thereof, the opposite side of said intermediate supporting portion resting against the abutments of the contact holder, a latch member movably disposed within said holder having a bossed surface portion projecting from one side thereof, said latch member releasably engaging said switch for releasably holding said contact holder therein, and a spring bearing against said contact member in a direction to maintain said contact member yieldingly against said abutments, said spring being releasably held at its opposite ends by encircling the projecting boss of the contact member and the projecting bossed surface of the latch.

10. In a switch, an insulation member having a recess, and a contact structure unit removably mounted in said recess, said contact structure comprising a holder, a contact member mounted in said holder, and a latching member carried by said holder and releasably engaging a part of said insulation member for releasably holding said contact structure unit in said recess, said holder having a part slidably abutting the bottom of said recess, part of the holder having an opening, and said latching member having a tongue projecting through said opening and having a releasable latching engagement with the bottom of said recess.

11. In a switch, an insulation member having a recess, and a contact structure unit removably mounted in said recess, said contact structure comprising a holder, a contact member mounted in said holder, and a latching member carried by said holder and releasably engaging a part of

said insulation member for releasably holding said contact structure unit in said recess, said holder having a part slidably abutting the bottom of said recess, part of the holder having an opening, and said latching member having a tongue projecting through said opening and having a releasable latching engagement with the bottom of said recess, said contact member and said latching member being movably mounted in said holder in spaced confronting relation, and spring means disposed between said contact member and said latching member and yieldably holding them in their operative positions.

12. In a switch, an insulation member having a recess, and a contact structure unit removably mounted in said recess, said contact structure comprising a holder, a contact member mounted in said holder, and a latching member carried by said holder and releasably engaging a part of said insulation member for releasably holding said contact structure unit in said recess, said holder having a part slidably abutting the bottom of said recess, part of the holder having an opening, and said latching member having a tongue projecting through said opening and having a releasable latching engagement with the bottom of said recess, said contact member and said latching member being movably mounted in said holder in spaced confronting relation, and spring means disposed between said contact member and said latching member and yieldably holding them in their operative positions.

13. In a switch, an insulation member having a recess, and a contact structure unit removably mounted in said recess, said contact structure comprising a holder, a contact member mounted in said holder, and a latching member carried by said holder and releasably engaging a part of said insulation member for releasably holding said contact structure unit in said recess, said holder and said latching member terminating in forward free ends relatively movable toward each other at the front of said insulation member for releasing said latching member from said insulation member.

14. In a switch, an insulation member having a recess, and a contact structure unit removably mounted in said recess, said contact structure comprising a holder, a contact member mounted in said holder, and a latching member carried by said holder and releasably engaging a part of said insulation member for releasably holding said contact structure unit in said recess, said recess having a front opening and said insulation member having a part at the rear end of said recess engageable by said holder, spring means resiliently pressing said holder and said latching member against each other and also releasably holding said latching member in engagement with said insulation member, said holder and said latching member terminating in forward free ends relatively movable toward each other at the front of said insulation member for releasing said latching member from said insulation member.

15. In an electric switch, an insulating supporting carriage, a contact holder having an abutment member in normal engagement with said carriage and spaced upstanding arms pro-

vided with inturned projections at the upper ends of said arms, a contact member located between said arms and in normal engagement with said projections, a latch member located between said arms and in normal engagement with said abutment and said supporting carriage, and spring means yieldingly holding said contact member in the aforesaid relation, said spring means also in collaboration with said latch constituting the means of locking said abutment member onto said supporting carriage, said abutment member of said contact holder having a rear part extending outwardly beyond said latch member and engageable with a part of said carriage, said contact holder and said latch member terminating in forward free ends relatively movable toward each other at the front of the carriage for releasing said latch member from said engagement thereof with said carriage.
